UNITED STATES PATENT OFFICE.

ROBERT W. SCOTT, OF BOSTON, MASSACHUSETTS, ASSIGNOR TO SCOTT & WILLIAMS, INCORPORATED, A CORPORATION OF MASSACHUSETTS.

STRIPING ATTACHMENT FOR KNITTING-MACHINES.

1,236,770.

Specification of Letters Patent. Patented Aug. 14, 1917.

Application filed July 28, 1915. Serial No. 42,400.

To all whom it may concern:

Be it known that I, ROBERT W. SCOTT, a citizen of the United States, and resident of Boston, in the county of Suffolk and State of Massachusetts, have invented new and useful Improvements in Striping Attachments for Knitting-Machines, of which the following is a specification.

My invention relates to knitting machines having devices for changing the kind of fabric automatically to produce a stripe or stripes.

One object of my invention is to provide an attachment for existing machines capable of automatically operating the yarn carriers or guides of said machines and their auxiliary devices to produce by a succession of yarn-changes stripes or groups of stripes placed in the product automatically at a predetermined part or parts of the fabric, the pattern knit and the location of the pattern in the fabric being changeable at will. Another object is to provide independent pattern means readily attachable to a knitting machine having a primary pattern surface for control by said primary surface, independently to effect in the fabric changes of structure for ornament, in addition to the changes provided for by the machine devices proper.

In the accompanying drawings,

Figure 1 is a right side elevation of a knitting machine equipped with my new devices;

Fig. 2 is a detail in section on the line 2—2 of Fig. 3 showing another position of the parts;

Fig. 3 is a plan; and

Fig. 4 is a left side elevation showing a modified actuating device for the attachable pattern surface.

For purposes of explanation of one use only of my new devices, I have shown them as applied to a hosiery knitting machine, of which only those parts necessary to an understanding of the new device are shown. The machine frame A has a bearing at a for a shaft (not shown) actuated to drive the movable element of a knitting head H mounted on the frame, which also supports a cam or pattern shaft D' carrying certain pattern indications, and intermittently rotated through a whole or less than a whole revolution for each article by a pawl r^2 engaging a rack wheel (not shown) fast to

shaft D', said pawl being active when a pawl-controller k is lifted by indications p, p' carried by a primary pattern surface such as chain P, which is constantly advanced step by step by a ratchet r and pawl r' , all as usual in the art, the pawls r' and r^2 being conveniently pivoted on a part of oscillating sector S driven from the driving means.

Shaft D' drives in any suitable manner, as by gearing g a main pattern surface, such as drum D, which in the usual construction shown rotates upon a shaft D² also serving as a center for sector S, which is oscillated to drive the primary pattern and main pattern advancing ratchets, and to move the movable element of head H for reciprocatory knitting, all as usual in the art.

The main pattern surface actuates yarn-guides or carriers F and other devices such as a yarn severing and clamp device C. In the machine shown, the connections for operating the devices C and F are thrust-bars T independently movable by cams on drum D to throw each yarn guide F to an upper inoperative position and to actuate severing device C to sever and hold the yarn removed from work, but the devices now to be described may be applied without substantial change to other forms of operating connections for equivalent yarn-guides.

A bracket 1 for attachment by a single screw 2 to the upper surface of frame A is provided with depending arms 3 and a transverse member 4 having a boss 5 bored to receive the lower end of the usual supporting rod V of the overhead yarn-guiding devices. Arms 3 end in bosses 6 bored for bearings for an auxiliary pattern shaft 8, which is thus attachably supported at the back of the machine near the drum D and parallel to its axis. Member 4 is provided with a boss 7 bored to hold rigidly a stud shaft 9 above shaft 8 and extending past the rear sides of bars T.

Shaft 8 has rigidly attached to it a ratchet wheel 10, and an auxiliary pattern surface preferably made up as shown of sprocket wheels 10, of any desired number, shown as four, each carrying a mutable-link pattern-chain 15 having lugs 16 forming together elevated surfaces which may be of any desired changeable lengths with respect to the whole length of the chain, which in turn may

be varied in length, dependent upon the desired length of the series of changes making up one unit or repeat of the pattern in the fabric.

5 Shaft 9 carries a series of indicator levers 18, one for each chain 15, each having at its lower end a transverse channel for a chain-reading nose 20 adjustable by a screw 22 and fixed by a set screw 21; and each having a 10 transverse channel for an arm 19 held for adjustment by screw 23.

Arms 19 are suitably bent each to extend into a notch 25 formed in the rear face of the thrust-bar leading to the yarn-guide or 15 other instrument to be controlled. As shown, three arms 19 control three yarn-guides F, and one arm 19' controls severing device C.

It will be observed that the connection 20 formed by levers 18 and arms 19 between the auxiliary pattern and the devices to be worked is positive in one direction only, the bars T being free for operation by the main pattern except when cam lugs 16 cause 25 the connection 18, 19 to lift their respective bars T. The yarn-guides F are made inoperative by lifting their bars, while the severing device C opens to receive the yarn on lifting, and cuts and clamps on dropping 30 its bar. Lowering movements of the bars being by gravity or springs, cams on the surface D and cams on the auxiliary surface 15 may actuate the devices F and C independently or together, the presence of a 35 cam on either surface preventing the return of the bar moved by it, whatever the indication of the other surface may be.

One important use of the auxiliary surface 15 is to enable a relatively large number of or rapid movements of connections 40 such as the bars T without requiring movement of the main pattern, such as drum D, the necessary shifts and changes of parts for some classes of product taking up such 45 an extent of motion of the main pattern as to leave no large part of it free to be devoted to movements for a number of incidental rapid changes or shifts of the parts operated by it, such as are necessary for an ornamental pattern. By my new construction, each group of special or incidental actuations of such mechanisms as the devices F and C can be carried out either 50 during passage by the connections of, or 55 stoppage of the main pattern at a place having no actuating cams for those connections to be specially moved at that time by the auxiliary pattern.

My device provides for actuation of the 60 auxiliary pattern at predetermined times independently of motions of the main pattern surface, thereby avoiding moving the main pattern system for the purpose of stopping and starting the auxiliary pattern and 65 leaving the main pattern free to be operated

for any desired changes in the knitting during independent functioning of the auxiliary pattern devices. It may, for instance, be desired to move the main pattern to operate some one of the connections T to cause 70 the special actuation of one of the yarn guides F for splicing, during the uninterrupted movement of other connections T for striping; or during rapid shifting of some or all of the connections T it may be desired to move the main pattern repeatedly to change the length of stitch, or to make other shifts of the mechanisms. For the above and other purposes, I have provided for the control of actuation of the auxiliary 80 pattern from the primary pattern surface.

The ratchet 10 is driven by a pawl 30, which may be a hooked pawl, as shown, pivoted to the sector S on the same stud r^2 as the pawl r^2 actuating the main pattern 85 system D', D², D. Pawl 30 normally swings free of its ratchet, as illustrated in Figs. 1 and 2, being suspended against gravity by a collapsed tension spring 31, of sufficient strength not to be extended by the 90 weight of the pawl, hooked to the pawl at one end, and at the other end to one arm of a bell-crank lever 32 loose on shaft 8, and normally in the position shown in said figures. The other arm of lever 32 is bored 95 for a tension rod 33 having an adjustment nut 34.

A bracket 36 at the front of the machine has pivoted to it at 35 a follower lever 37 having a follower lug 38 taking over one 100 side of the chain P, and a lug 39 carrying a limit screw 40 taking against frame A.

Tension rod 33 passes through the machine frame and is hooked into a hole 42 in follower lever 37, gravity of pawl 30 105 maintaining lever 37 in the adjusted position set by screw 40, the stroke of the pawl being on a line too low to engage a tooth of wheel 10. Changeable links of chain P are provided at the desired points representing 110 times in the operation and places in the product, with lugs 41 adapted to be bridged from link to link by follower lug 38. Presence of one or more lugs 41 at follower 115 38 rocks lever 32 and lifts pawl 30 into engagement with the ratchet at the extreme of its stroke, spring 31 now stretching to hold the pawl on the ratchet. Any usual form of brake, as at 11, may be employed to prevent overthrow of the auxiliary pattern shaft 8 120 and its attachments.

For transverse stripes in the stocking or other product knit, the respective chains 15 will usually be made up to present lugs 16 to swing all except one of the indicator levers 18 for the yarn guide connections, to leave one yarn guide in operation. When the pattern is to determine a yarn change, the chain 15 controlling the guide to be inserted presents no lug, and the chain for the 130

guide to be removed at the next following tooth of its sprocket 12 has a lug 16. A sufficient interval of time during the advance of shaft 8 between dropping one indicator 18 and bar T and lifting the other indicator and its bar is thus secured to interknit both yarns on the same needles for a short distance. Motions of pawl 30 and sector S are so related to the rotation of the 5 rotary element of knitting head H as to localize these points of change at one part of the knit tube, usually the back of the leg if the product is a stocking.

Whenever the yarn is changed for a stripe, 10 it is desirable to operate the cutter and clamp device C, and for this purpose that chain 15 selected to control the device C may be provided with a lug 16 relatively at the same position as a lug for entering the 15 new yarn on another chain 15.

It will be understood without further description that the shaft 8 may be turned step by step to move the bars T by the passage of the whole or any part of the pattern 20 set on the chains 15, the time and duration of the movement of the bars T depending upon the placing and number of the links 25 41 on the primary surface P.

Presence of a cam on the main pattern D 30 under one or more of the connections T at the time of actuation of the auxiliary pattern may be employed if desired to prevent the operation of that bar, but the pattern D is usually arranged to free all of the 35 connections intended to be worked by the auxiliary pattern when or after the shaft 8 has begun to move. Movement of the main pattern for this purpose may be that utilized to work some other connection than those intended to be controlled by the auxiliary pattern.

When the machine is employed for knitting articles in succession, I may use the auxiliary pattern to select that yarn guide 40 to be employed at the beginning of each article, by racking the shaft 8 to the desired position of the auxiliary pattern during the idle running of the machine between successive seasons of knitting or during knitting 45 of waste fabric between two articles, automatic means for this purpose comprising a series of links 41 on chain P placed to move shaft 8 at this time. By this means the end of the pattern may leave in use a yarn of a 50 different color or kind from that knit prior to the pattern.

For a pattern of stripes at the middle of the leg of a woman's stocking, for instance, one of the indicator levers 18 may be left in place to cause a guide F to feed a black cotton yarn for the top of the leg; shaft 8 55 may then be turned to produce a succession of stripes of yarns of other colors or kinds, recurring if desired to the black yarn as a ground color, and the last movement of the

shaft 8 may leave in use for the remainder of the leg a silk yarn, which may or may not have been fed for one of the stripes. A single step of shaft 8 may be employed at any part of the cycle of knitting operations 70 to change any of the yarns controlled by the auxiliary pattern, if desired, and any part of the auxiliary pattern for such occasional use may be moved past the indicators 18 during presence of cams on the main pattern 75 holding all of the yarn-guides under the influence of the auxiliary pattern out of action, thereby enabling any part of the pattern on the chains 15 to be stopped out, while permitting an indefinite repeat of the 80 remainder.

In the usual construction of machines such as that shown, the sector S makes a forward beat, by which the pawl 30 may move the auxiliary pattern, once in each of a plurality 85 of revolutions of the knitting head. Usually this interval will not be too large for the thinnest stripe, (for instance four courses thick) to be knit.

I may if desired move the shaft 8 and the auxiliary pattern at shorter intervals, one construction for this purpose being that shown in Fig. 4. The bracket 1 and the pattern surface 15 may be the same as above described, but shaft 8 is extended toward the 90 left side of the machine to receive a ratchet 45 in the plane of existing gearing of the machine, such as the gear h driven from a pinion on main drive shaft B. The gear h may be a part of the speed-changing or the 95 rotary-reciprocating devices, as shown being that employed to drive the sector S through a crank and pitman, and making one revolution to four of the shaft B and the knitting head H. On any convenient stud such as 100 105 one end of shaft D² a pawl arm 47 having a follower lug 48 is held by a spring 49 against a series of like cams removably attached to the face of gear h. There may be any convenient number of cams 46, depending on the number of revolutions of the knitting head desired to occur during the narrowest stripe. Arm 47 is oscillated at the 110 passage of each cam.

A driving pawl 50 pivoted to arm 47 normally is restrained from contact with ratchet 45 by a controller arm 51 rigid with bell-crank 32 on shaft 8, held by spring 52 extending between an arm 53 fast in bracket 1 and an arm of said bell-crank. Whenever 120 a lug 41 on surface P pulls rod 33, arm 51 permits pawl 50 to advance the ratchet 45.

In order to cause the passage of the end of a series of lugs 16 to place a yarn-guide F in operation and the beginning of another 125 series of lugs 16 to remove the yarn-guide F going out of work to be separated by sufficient time to overlap the outgoing and incoming yarns on several needles, cams 46 may have leading ends of a gradual slope as 130

- shown, or of two stages of ascent separated by a dwell. Any suitable form of brake may be applied to any part of the system rotating with shaft 8.
5. What I claim is:
1. A knitting machine having a primary pattern surface, and an auxiliary pattern surface; a series of knitting devices adapted to be operated severally in an independent order by both the main pattern surface and the auxiliary surface, and means controlled by said primary pattern surface for operating said main and auxiliary surfaces at independent predetermined times.
  10. 2. In a knitting machine having a main pattern surface and a primary pattern surface controlling the motions of said main surface, a plurality of yarn carriers, and connections for moving said yarn carriers from said main surface, an auxiliary pattern surface and means whereby said auxiliary surface may operate said connections when active, in combination with means co-acting with said primary surface for rendering said auxiliary surface active and inactive at predetermined times.
  15. 3. In an automatic knitting machine, yarn feeding means pattern-controlled by devices moving at times during the production of an article to determine the yarn fed for an extensive part of each article, in combination with auxiliary pattern means also controlling said yarn feeding means for a series of rapid changes adapted for operation independently of said pattern-controlled devices, primary pattern means and independent connections therefrom to said devices and said auxiliary pattern means.
  20. 4. A knitting machine having a plurality of movable yarn carriers, auxiliary pattern means for controlling the active and inactive positions of said carriers to produce a pattern in the fabric, said auxiliary pattern means being adapted to select and actively position any one of said carriers during the production of extended areas of fabric, in combination with means independent of said auxiliary pattern means for maintaining any one of said carriers in active or inactive position.
  25. 5. A knitting machine having a series of independent connections movable positively in one direction and knitting devices adjustable by said movement, a main pattern surface for severally moving said connections, and an auxiliary pattern mechanism having a pattern surface adapted to be intermittently advanced and elements contacting with said connections positively when moved in said direction, said elements being free of said connections when moved in an opposite direction.
  30. 6. A knitting machine having a plurality of yarn carriers and a yarn severing mechanism, in combination with main and auxiliary pattern means for severally and independently operating both said carriers and said mechanisms.
  35. 7. A knitting machine having knitting means, yarn feeding devices, a primary pattern surface, and main pattern mechanism for controlling said means and devices, in combination with an auxiliary pattern mechanism adapted to be attached to the machine for intermittent movement under control by said primary pattern surface, and comprising means for operating said yarn feeding devices additionally and independently of said main pattern devices at desired times.
  40. 8. In combination in a knitting machine, a series of yarn carriers, a series of thrust-bars, a pattern surface, and means on said surface operating directly on said thrust-bars to move said yarn-carriers; an auxiliary pattern surface, means to advance said surface step by step, and a series of indicator members each adapted when moved by said auxiliary surface, to move a thrust-bar to operate one of said yarn-carriers.
  45. 9. An automatic knitting machine having means comprising yarn feeding devices and main pattern devices for knitting a succession of articles or fabrics, in combination with an auxiliary pattern mechanism adapted to control said yarn feeding devices to feed a succession of different yarns during knitting of each article or fabric, and means for changing the position of said auxiliary pattern mechanism between successive articles; whereby the pattern in the fabric may be preceded and followed by fabric knit from different yarns.
  50. 10. An auxiliary pattern device for attachment to knitting machines adapted to be controlled by a primary or master pattern of said machine comprising an auxiliary pattern surface, a ratchet mechanism for advancing said surface, controlling means for said mechanism for connection to said machine, and a series of indicator levers each adapted to engage said auxiliary pattern device and to engage positively in one direction one of a plurality of connections between the knitting devices and the pattern devices of said machine.
- Signed by me at Boston, Massachusetts, this twenty-seventh day of July, 1915.
- ROBERT W. SCOTT.
